MOTEL BUILDING

Herman Baehre, Chicago, Ill.

Application June 29, 1954, Serial No. 31,215

Term of patent 14 years

(Cl. D13—1)

Fig. 1.

Fig. 2.

To all whom it may concern:

Be it known that I, Herman Baehre, a citizen of the United States and a resident of Chicago, in the county of Cook and State of Illinois, have invented a new, original, and ornamental Design for a Motel Building, of which the following is a specification, reference being had to the accompanying drawing, forming a part thereof, and in which:

Fig. 1 is a perspective view of a motel building showing my new design;

Fig. 2 is a top plan view of the same.

The opposite side of the building is similar to the side

shown and the rear is plain, except for the duplication of the wall design as shown.

I claim:

The ornamental design for a motel building, as shown and described.
